CASTING WHEEL CONTROL

Karl A. Lindner, Baltimore, Md., assignor to
American Smelting and Refining Company,
New York, N. Y., a corporation of New Jersey

Application October 8, 1937, Serial No. 167,927

3 Claims. (Cl. 22—63)

This invention relates to a control for a casting wheel of the type used for intermittently casting metal shapes at a plurality of successive stations. The invention may be applied to any casting wheel of the above type, such as a wheel for casting copper cakes, copper wire bars, copper or lead anodes or the like.

An object of the invention is to provide an automatic control for an intermittently driven casting wheel of the above type.

Another object is to provide means for automatically stopping the wheel at exact casting positions.

Another object is to provide means for gradually accelerating and decelerating the wheel so as to obtain a smooth and uniform operation with a minimum vibration.

Another object is to provide for the automatic shifting of the casting wheel between successive stations in response to the mere pressing of a button or closing of a switch.

Another object is to provide a novel and improved mechanism of the type above indicated.

Various other objects and advantages will be apparent as the nature of the invention is more fully disclosed.

Although the novel features which are believed to be characteristic of this invention are pointed out more particularly in the claims appended hereto, the invention itself will be better understood by referring to the following description, taken in connection with the accompanying drawings, in which a specific embodiment of the invention has been set forth for purposes of illustration.

In the drawings:

Fig. 1 is a plan view of a typical casting wheel of the type used for casting copper cakes;

Fig. 2 is a diagrammatic chart indicating the different operating positions of the casting wheel; and

Fig. 3 is a schematic diagram showing the electrical control circuit embodying the present invention.

In the following description and in the claims certain specific terms are used for convenience in referring to various details of the invention. These terms, however, are to be given as broad an interpretation as the state of the art will permit.

Referring to the drawings more in detail, the invention is shown as applied to a casting wheel of the type used for the vertical casting of copper cakes, although it is to be understood that this particular type of casting wheel is shown only for purposes of illustration and that this invention is applicable to various types of casting wheels which are intermittently shifted between a plurality of successive casting stations.

In the embodiment shown in Fig. 1 the casting wheel comprises a circular frame 10 carrying a plurality of separate molds 11 which are adapted to be used for casting a metal shape such as, for example, a copper cake. Each mold 11 is supported by a bracket 12 which is rotatably mounted by means of trunnions 13 in the frame 10. The frame 10 and the molds above described are carried by a bull ring 14 having internal driving teeth 15. The bull ring 14 is supported by a pair of rollers 16 mounted on suitable brackets 17 carried by a spider 18 and is driven by a pair of spur gears 19 actuated through suitable gear reduction means 20 by driving motors 21 which are likewise mounted on the spider 18.

The molds 11 are provided with tilting levers 25 which are adapted to engage stationary dump guides 26 to invert the molds for discharging the cast shapes, and to engage righting guides 27 for reinverting the molds to upright position to receive another casting. The molds are shown as of the water-cooling type, water being supplied through an inlet pipe 30, thence through pipes 31 and manifold pipes 32 to suitable connections (not shown) in the brackets 12. The water supply is controlled by a suitable valve (not shown) which is actuated automatically in accordance with the position of the wheel to supply cooling water during the time that the mold is in upright position and while the metal is being cooled therein, but to shut off the supply of cooling water when the mold is inverted for dumping the casting and while the mold is in the inverted position for cleaning and receiving the mold wash.

In the embodiment shown means are provided for pouring two molds at a time. This comprises a pouring spout 35 having a pair of discharge nozzles 36 which supply the molten metal to a pouring ladle 37, arranged to direct the metal into the two molds 11a in casting position. The pouring spout and ladle may be filled with charcoal or other suitable deoxidizing material to prevent oxidation of the molten metal as is well known in the art. The metal shapes which are discharged from the molds are removed by a conveyor 40 which is driven through suitable gearing 41 by a motor 42.

The operation of this wheel for casting purposes is shown diagrammatically in Fig. 2 in which the pouring point is indicated by the line 50. The cooling zone extends between this line and 55

the line 51. In the positions represented by the angle 52 the molds are inverted for dumping purposes. The zone represented by the angle 53 constitutes the cleaning zone in which the molds may be cleaned by scraping or the like. The zone represented by the angle 54 constitutes the washing zone in which a suitable mold wash is applied to the mold cavity prior to casting the cakes therein. In the zone represented by the angle 55 the molds are again returned to upright position for receiving the molten metal. The valve, controlling the cooling water, is open for a period represented by the angle 56 which corresponds in general to the time during which the mold is in upright position. It will be noted that the valve is opened at the time the molds are returned to upright position and is closed just before the molds are inverted for dumping.

It is to be understood that a conventional type of casting wheel has been described above for convenience. The wheel may be mounted or driven in other ways and the molds may or may not be water cooled. While the molds have been shown as pivotally mounted to be dumped by inversion, it is to be understood that in certain instances the molds may be dumped by providing the mold with a removable bottom which is suitably opened and closed at the proper positions of the wheel. Suitable mechanism may also be used for opening and closing the water control valve, such for example, as a cam track engaging a control member at suitable positions of the wheel. It is further to be understood that any desired number of molds may be arranged to be filled at the same time depending upon the size of the molds and of the wheel and that the invention is not limited to the simultaneous casting of two molds, as shown in the drawings.

The present invention provides means for automatically controlling the driving motors 21 so as to drive the frame 10 and the various molds to bring successive molds into casting position. In the form shown the control is effected by means of a flag 60 which is driven by a gear 61 from the bull ring 14 at a gear ratio such that the gear 61 and the flag 60 make a complete revolution while the casting machine is being driven from one casting station to the next. The flag 60 is adapted to intercept successively the light rays to a pair of photoelectric cells 62 and 63 constituting the deceleration control and stop control respectively.

The control as shown more in detail in Fig. 3, comprises a motor generator set 70 supplying current to drive the motors 21. The current supplied by the generator is controlled by a starting switch 71, by the deceleration control photoelectric cell 62, and by the stop control photoelectric cell 63.

The motor generator set 70 comprises a driving motor 72 actuated by any suitable source of current and driving a generator 73 and an exciter 74. The exciter 74 is provided with the usual shunt field 75 and supplies current to lines 76 and 77. The switch 71 connects relays 78 and 79 across the lines 76 and 77 by means of leads 80 and 81. The relay 78, when energized, closes a circuit from the line 76, through lines 78a and 78b, contactors 88¹, and line 78c back to the line 77, thereby closing contacts 82 and 83 of the contactor 88. The contact 83 closes a circuit from the generator 73 to the motors 21. The contact 82 closes a circuit from the lines 76 and 77 to the field winding 84 of the generator 73 through a potentiometer 85. The potentiometer 85 has a

contact 86 driven by a motor 87 to variably increase or decrease the excitation applied to the field winding 84 and to correspondingly vary the current supplied by the generator 73 to the motors 21.

The relay 79 is of the reversing type and is adapted, when closed by the closing of the switch 71, to connect the motor 87 across the lines 76 and 77 so as to cause the motor to rotate in a direction to cause the contact 86 to progressively decrease the effective resistance of the potentiometer 85, thereby progressively increasing the excitation of the field winding 84 until full voltage is applied thereto. The generator 73 accordingly supplies an increasing current to the motors 21 which causes the motors to smoothly accelerate to a maximum speed. When the contact 86 reaches its end position the motor 87 is automatically stopped by a stop control, not shown, which is actuated by said contact.

With the motors 21 operating at full speed the casting wheel is driven until the flag 60 registers with the light beam applied from a suitable source, not shown, to the photoelectric cell 62. When this occurs the light applied to the photoelectric cell 62 is interrupted and the photoelectric cell operates through a relay 90 to reverse the relay 79 so as to cause reverse rotation of the motor 87, thereby moving the contact 86 in a direction to gradually decrease the excitation of the field winding 84. The motors 21 are thereby gradually decelerated.

The further rotation of the casting wheel during the deceleration period causes further movement of the flag 60 until this flag intercepts the light rays applied from a source (not shown) to the photoelectric cell 63. When this occurs the photoelectric cell 63 acts through a relay 91 to open the relay 78, thereby releasing the contact 88¹, opening the contacts 82 and 83, breaking the current supply to the motors 21 and instantly stopping the casting wheel. The system is then ready to repeat its cycle of operation when the switch 71 is again closed.

It is to be noted that by this system the motors 21 are gradually accelerated and decelerated. The casting wheel is accordingly smoothly driven between successive casting stations. Vibration and jerking of the molds in their movement is avoided thus preventing agitation, spilling or other undesirable movement of the cast metal which would result from sudden starting or stopping of the wheel. Furthermore, the casting wheel is stopped at the exact casting position by the correct timing of the flag 60 with respect to the stop control photoelectric cell 63. The deceleration is so controlled that the motors 21 have been brought to a substantial stop by the time the stop control circuit is actuated. It is to be understood that the photoelectric cells 62 and 63 are spaced as required to effect the above operation. They have been shown as arranged diametrically opposite for purposes of illustration only.

In this system the motors 21 are caused to automatically carry out the above described cycle of operation. For shifting the casting wheel it is only necessary to close the switch 71 which may constitute a push button, and thereafter the casting wheel is automatically driven to the next casting station and is stopped in position to receive the next casting. The casting operation is speeded up because it is not necessary for the operator to slow down and stop the casting wheel or to "feel" for the correct casting posi-

- tion. The above described system accordingly eliminates all mechanical manipulations and results in the continued and uniform operation of the control mechanism for the purpose specified.
- 5 It is to be understood that other specific types of control can be substituted for that set forth above. For example, mechanical switches can be used in place of photoelectric cells and stop means may be carried by either the bull ring 14 or the frame 10 or any other suitable part of the apparatus in a position to engage the mechanical switches and actuate the same at the designated deceleration and stop positions. Furthermore, the relay arrangement can be varied to constitute, for example, a standard starting box which may be arranged for reverse actuation for the gradual deceleration and stopping of the motors. In that event, the motors 21 may be supplied directly from a supply main.
- 10 A motor generator set has been shown and described merely for convenience. If a standard starting box is employed, the motor 87 and potentiometer 85 may be substituted thereby. It is also to be understood that any suitable type 15 of reversing relay may be used for causing the reversible operation of the motor 87. Such relays are well known in the art and consequently the construction thereof has not been set forth herein.
- 20 Although a particular embodiment of the invention has been shown for purposes of illustration, it is to be understood that various changes and modifications may be made therein by those skilled in the art without departing 25 from the invention as defined in the appended claims.

What is claimed is:

1. Apparatus for casting metal shapes at a plurality of stations comprising the combination 40 with a casting wheel upon which a plurality of molds are mounted, of driving means for said wheel including a plurality of electric motors, said motors being connected in series and pro-

viding their own load balance from a common source of power, means to energize and to gradually and evenly accelerate said motors to top speed, and means actuated by said wheel when the latter reaches a predetermined position for gradually and evenly decelerating said motors to lowest speed, and means actuated by said wheel when said wheel reaches a casting station for stopping the same.

2. A control for a casting wheel for successively casting metal shapes comprising a driving motor for said wheel, a generator supplying power for said motor, a contactor closing the circuit between said generator and said motor for causing actuation of said motor, means supplying a gradually increasing excitation to the field winding of said generator for causing said motor to gradually accelerate until maximum speed is attained, means actuated by the casting wheel for gradually decreasing the excitation of said generator 15 for decelerating said motor until minimum speed is attained, and means interrupting the circuit between said generator and motor when said wheel reaches a predetermined position.

3. A control for a casting wheel for casting 25 metal shapes comprising a motor driving said casting wheel, a generator supplying power for operating said motor, a variable potentiometer controlling the field excitation of said generator, means closing the circuit from said generator to 30 said motor for starting the latter, means actuating said potentiometer for gradually increasing the field excitation of said generator so as to gradually accelerate said motor until top speed is reached, means actuated by said wheel reversing 35 said potentiometer for decreasing the field excitation of said generator and gradually decelerating said motor until lowest speed is reached, and means interrupting the circuit between said generator and said motor for stopping the latter.

KARL A. LINDNER.
